J. H. ZIMMER

BURNER

Filed June 17, 1922

UNITED STATES PATENT OFFICE.

JOHN H. ZIMMER, OF ST. LOUIS, MISSOURI.

BURNER.

Application filed June 17, 1922. Serial No. 568,955.

To all whom it may concern:

Be it known that I, JOHN H. ZIMMER, a citizen of the United States of America, a resident of the city of St. Louis, in the State of Missouri, have invented certain new and useful Improvements in Burners, of which the following is a full, clear, and exact description, reference being had to the accompanying drawings, forming part of this specification.

This invention relates to improvements in gas burners, and has for its object the increase of the heat energy, or heat-producing power, of the gas flame of a burner.

Briefly stated, the invention consists in providing a gas burner with an open or unconfined air gap of measurable extent between the gas tip and a constantly burning lighter, the ignition taking place at the lighter and the base of the flame remaining opposite said lighter, leaving the air gap free for the commingling of gas and atmospheric air drawn from the surrounding medium by the current of the jet.

With the foregoing and other objects in view, the invention comprises the novel construction, combination and arrangement of parts hereinafter more specifically described and illustrated in the accompanying drawings wherein is shown the preferred embodiment of the invention. However, it is to be understood that the invention comprehends changes, variations and modifications which come within the scope of the claims hereunto appended.

Fig. I is a plan view of the gas burner.

Fig. II is a section on line II-II of Fig. I.

Fig. III is a side elevation of the gas burner.

Referring to the drawings, 1 designates a base or stand for the support of the burner and its accessories. The tip 2 is provided at its lower end with screw threads, which permits said tip to be secured to said base 1. Communicating with the passageway in the tip is a gas passageway 3 which passes through the base 1 and is in communication with the passageway through the stop-cock 4, screwed into said base 1. The outer end

of the stop-cock 4 is provided with an extension 4' adapted to receive an end of a hose or other gas conductor which will be connected to the gas supply.

Extending upwardly from the base 1 is 55 a rigid supporting member 5 which supports the lighter duct 6, said supporting member being provided with an opening 5' through which an offset portion 6' of said lighter duct extends. One end portion 7 of the 60 lighter duct 6 extends in a direction toward the tip 2, the outer end of said portion 7 terminating a little to one side of the path of the jet from said tip, and the other end portion 8 of said lighter duct, which is located on the opposite side of the supporting member 5 extends rearwardly from said supporting member. Passing downwardly through the upper portion of the supporting member 5 is a set screw 9 adapted to bear 65 against the portion 6' of the lighter duct whereby the outer end of the lighter duct may be located in different positions relative to the tip 2.

Extended through the wall of the portion 4' of the stop-cock 4 is a nipple 10, said nipple being in free communication with that portion of the gas passageway in said stop-cock beyond the valve mechanism, thereby permitting a flow of gas from the 70 passageway through the nipple 10 at all times. Connecting the nipple 10 with the end portion 8 of the lighter duct 6 is a flexible tube 11 whereby said portion 8 may be raised and lowered for a purpose to be 75 hereinafter described. In the event that it is desired to stop the flow of gas through the lighter duct 6, the threaded member 12 may be screwed inwardly until the pointed end 13 thereof enters the inner end of the 80 nipple 10.

To provide a means for supporting the articles being subjected to the flame, I provide a member 14 which is supported in any suitable manner by the base 1.

The operation of my device is as follows:

The lighter 6 being ignited and the stop-cock opened, a stream of gas will be forced up through the air gap gathering atmospheric air freely from all surrounding points

on the way, and reaching the lighter will be ignited and burn with an intense heat, about 572° above that of the ordinary Bunsen burner. The explanation of the high temperature is found in the fact that it is possible to obtain a perfect mixture of gas and air. In an ordinary Bunsen burner the gas passes upwardly in a tube and the air is drawn into said tube at the lower portion thereof, but owing to the restricted space within which said gas and air pass, they are not properly mixed, the center of the upwardly moving fluid body being practically pure gas while the outer sheath is practically pure air. In the operation of the device herein disclosed, the gas issues from the tip in a fan-shape, and it is possible for the gas and air to be thoroughly mixed before same reaches the lighter. The action of the apparatus depends upon the distance of the end of the lighter from the tip. No definite rule can be given for determining this distance, it being a matter of adjustment within certain limits. If the lighter is too far away it will fail to ignite the gas, which may have absorbed too much air; if it is too near there will be little increase over the ordinary Bunsen flame, and in fact, there is danger of ignition at the tip 2, when the heat will be that of a common gas burner. To get the best effects, therefore, and to enable the intensity of the flame to be controlled, the lighter end may be adjusted toward and away from the tip 2 by unscrewing the set screw 9 and rocking the portion 6' of the lighter duct within the opening 5' in the member 5, so as to move the end of said lighter duct toward or away from the tip 2, as suggested by dotted lines in Fig. II. After the tip of the lighter duct has been properly located, the set screw 9 may be again screwed downwardly until it bears against the portion 6' of the lighter duct 6, when said lighter duct will be fixed in place.

Under ordinary circumstances gas is always flowing through the lighter duct and said lighter duct is of such restricted diameter throughout, or at its extreme end, that it will supply but a very small flame, just sufficient for igniting purposes.

If the force of the flow of gas issuing from the tip 2 is not strong there may be a tendency for the flame to travel downwardly and burn at said tip. To prevent this I provide said tip with a plurality of slots 15 which extend downwardly from the point at which the gas issues from said tip. In operation the jet of gas passing through the armature 2 will draw air through the slots 15, which air will have the effect of entering under the flame and lifting same should said flame settle down on the tip 2.

I claim:

1. A burner comprising a tip, a conductor

for conducting a combustible under pressure to said tip, said tip being provided with an orifice of such size that a stream of combustible issues from said tip at a velocity greater than the velocity of flame propagation, and a lighter above said tip and separated therefrom by an unconfined air gap, said lighter being located at a point along the stream of combustible where the velocity of the combustible is approximately equal to the velocity of flame propagation in the stream of combustible at which point the combustible is ignited to produce a flame.

2. A burner comprising a tip, a conductor for conducting a combustible under pressure to said tip, said tip being provided with an orifice of such size that a stream of combustible issues from said tip at a velocity greater than the velocity of flame propagation, and a lighter above said tip and separated therefrom by an unconfined air gap, said lighter being located at one side of the path of the stream of combustible at a point along the stream of combustible where the velocity of the combustible is approximately equal to the velocity of flame propagation in the stream of combustible at which point the combustible is ignited to produce a flame.

3. A burner comprising a tip, a conductor for conducting a combustible under pressure to said tip, said tip being provided with an orifice of such size that a stream of combustible issues from said tip at a velocity greater than the velocity of flame propagation, a lighter above said tip and separated therefrom by an unconfined air gap, said lighter being located at a point along the stream of combustible where the velocity of the combustible is approximately equal to the velocity of flame propagation in the stream of combustible at which point the combustible is ignited to produce a flame, and means whereby said lighter may be adjusted toward and away from said tip.

4. A burner comprising a tip, a conductor for conducting a combustible under pressure to said tip, said tip being provided with an orifice of such size that a stream of combustible issues from said tip at a velocity greater than the velocity of flame propagation, a lighter above said tip and separated therefrom by an unconfined air gap, said lighter being located at a point along the stream of combustible where the velocity of the combustible is approximately equal to the velocity of flame propagation in the stream of combustible at which point the combustible is ignited to produce a flame, and means whereby said lighter may be adjusted toward and away from said tip, said means comprising a supporting member by which said lighter is piv-

totally supported, and means whereby the discharge end of said lighter may be fixed at different distances from said tip.

fined air gap through which a column of 10 unburned gas passes from said tip, said gas being ignited when it reaches said constantly burning lighter and burning only at that point.

5. In a burner, the combination of a tip provided with means for preventing the burning of the gas at the point where said gas issues from said tip, and a constantly burning lighter above said tip, said tip and said lighter being separated by an uncon-

In testimony that I claim the foregoing 1st I hereunto affix my signature.

JOHN H. ZIMMER.
